CLAIM

The ornamental design for a fixed-wing aircraft with trailing propellers as shown and described.

DESCRIPTION

FIG. 1 is an isometric view showing my design;

FIG. 2 is a top view thereof;

FIG. 3 is a bottom perspective view thereof;

FIG. 4 is a forward view thereof;

FIG. 5 is a rearward perspective view thereof;

FIG. 6 is a left perspective view thereof; and,

FIG. 7 is a right perspective view thereof.

The broken lines illustrate portions of the fixed-wing aircraft with trailing propellers that form no part of the claimed design
